UNITED STATES PATENT OFFICE.

MORTIMER M. ROBB, OF DULUTH, MINNESOTA.

ELEVATOR SAFETY DEVICE.

Application filed March 7, 1925. Serial No. 13,729.

To all whom it may concern:

Be it known that I, MORTIMER M. ROBB, a citizen of the United States, residing at Duluth, in the county of St. Louis and State of Minnesota, have invented certain new and useful Improvements in Elevator Safety Devices, of which the following is a specification, reference being had therein to the accompanying drawing.

10 This invention relates to safety locks for elevators, the same having special reference to passenger elevators such as used in modern office buildings, and the like.

15 The principal object of the invention is to provide simple mechanical means whereby it becomes impossible for an elevator operator to move the elevator either up or down at any time when the doors controlling the entrance to same are open.

20 Another object is to provide means for the automatic controlling of the doors to the elevator.

25 Still another object of the present invention is to provide such means whereby the least mechanism possible is essential at each floor, the elevator carrying the principal operable parts.

30 Other objects and advantages of the novel structure will appear in the further description of the invention.

35 The illustration shown in the accompanying drawing forming part of this application, in which like references indicate like parts, is that of a fragmental portion of an elevator and cooperative floor in a building.

1 represents a fragmental portion of a rectangularly shaped elevator, such as commonly found in office or like buildings, while 2 represents a floor of the building past which the elevator operates when vertically reciprocated within its shaft; the floor sill, at the elevator shaft, being illustrated at 3. 4 and 5 represent the elevator shaft doors on the floor 2, they travelling in opposite directions within the channel or slot 6 in the door sill 3, such doors being commonly made to operate in unison, that is to say, opening from each other and closing towards each other simultaneously; the mechanism for such operation not being here illustrated as it forms no part of my present invention, but is common construction in elevator shaft doors.

55 7 represents the control arm of the operating device of the elevator, the same being common in various forms of elevators, and is

pivoted at 8, and movable in either direction. When rocked forwardly on its pivotal connection 8, the elevator will proceed to operate in one direction, and when rotated oppositely the elevator will move in the opposite direction, but when in neutral position, or disposed vertically, the motion of the elevator ceases, except as to that motion which may be imparted to it by momentum.

Attached to the operating lever 7, as at 9, and intermediate of the free end and the pivotal point 8, is the horizontally disposed rod 10, pivotally connected as at 11 to the rocker arm 12, which is pivotally mounted in any desired manner to the innermost side of the elevator cage, as at 13. The lower end of the lever 12 is pivotally attached as at 14 to the vertically reciprocable rod 15 which extends through the bottom of the cage and is attached as at 16 to the bellcrank lever 17 mounted in any desired manner upon a shaft 18, attached to the under side of the bottom of the cage. To the vertically disposed arm of the bellcrank lever 17 is attached the horizontally disposed rod 19 extending across the bottom of the cage and beneath the door opening therein and attached as at 20 to the dog operating arm 21 pivoted at its upper end as at 22 to the front outer wall of the cage, there being a guiding extension 23 on said arm for a more secure mounting of same. This arm extends outwardly somewhat from the face of the cage and is slightly arcuate in form so that as it passes the upper edge of a floor sill, such as indicated at 3, it may cooperate with the roller 24 connected with the door dog 25, which is pivoted as at 26 upon the supporting plate 27 rigidly attached to the upper face of the sill 3. This door dog 25 extends normally diagonally across the sill with its free end in the path of the door 4 which is operable as before stated in the channel 6. The door dog 25 is provided with a crank arm 28 to which the pitman 29 is attached. The opposite end of this pitman is pivotally connected as at 30 to the horizontally reciprocal bar 31 which carries the roller 24, and this bar is held in its foremost position with the dog 25 as previously described by means of any suitable form of contractile spring 32.

By this means it is apparent that when the elevator is passing in either direction a floor thus equipped with the dog 25 (it being obvious that the operating lever 7 must be upon either one side or the other of central

position) the arm 21 will pass the roller 24 on the dog 25 without operating same and consequently not free the door 4 from its locked position which is normally maintained as previously described. However, if just prior to approaching a floor from either direction the operator has centered his lever 7 in stopping position which is necessary in the act of stopping, the arm 21 will be in its 10 farthestmost extended position and with sufficient force engage the roller 24 to rock the dog 25 and remove it from its locked engagement with the door 4, so that if the elevator stops as anticipated within a reasonable distance of level with the floor the doors of the elevator shaft will be automatically unlocked.

This reasonable distance may be governed as is obvious by the length of the engaging 20 portion of the arm 21 with the roller 24 and is preferably established at approximately three inches either above or below the floor, and if such distance is exceeded in either direction the doors will remain permanently 25 locked against opening from either side thereof.

Now to the opposite door 5, which as before stated is operated in conjunction with the door 4, is pivotally attached as at 33 a 30 lever 34, this pivotal connection permitting of rocking motion of the lever without its being moved longitudinally, and the opposite end of the lever is pivotally attached as at 35 to the upper face of the sill 3. The lever 34 is provided adjacent its lowermost 35 pivotal end with a pin-like roller 36 extending outwardly into the elevator shaft for cooperative engagement with the vertically disposed open faced trough 37. This trough 40 is mounted upon two horizontally reciprocal bars 38 and 39 which are slidably mounted within suitable guiding members 40 and 41 attached to the front outer wall of the elevator 1 adjacent one edge of the door opening 45 in said elevator. The bar 38 is attached as at 42 to the vertically disposed lever 43 pivoted at 44 to the elevator wall, and at its opposite end as at 45 pivoted to the crank arm 46 mounted on the horizontally disposed 50 shaft 47 which may be supported in any desired manner for rockably carrying the twin dog 48. This twin dog 48 is keyed to the shaft 47 and positioned adjacent the upper end of the rod 15 which may be slightly enlarged or squared as at 49 so that the arched 55 fingers of the dog 48 may straddle same to prevent rocking movement of the rocker arm 12.

Thus it will be seen that at any time the 60 roller 36 is within the trough 37 and the doors of the elevator shaft are closed, no cognizance of such fact is present respecting the operation of this control mechanism.

However should the doors of the elevator shaft be opened to any considerable extent 65 (this being predetermined as desired) the horizontal movement of the trough 37 will rock the shaft 47 and cause the fingers of the dog 48 to straddle the upper end of the rod 15, thus absolutely preventing movement of 70 the elevator operating arm 7, and, as before stated, if the elevator has not stopped in its proper relation to the floor the dog operating arm 21 will not have functioned in respect to the dog 25 and therefore the door 75 cannot be opened, thus providing absolutely dependable cooperation in respect to the functioning of the doors and the position of the elevator.

The trough and dog are retained in receptive position at all times for cooperation with the door, as previously described, by the use of the contractile spring 50.

From the foregoing it is apparent that I have devised a somewhat more practical device for the safe operation of elevators than that disclosed in my copending application Serial Number 1583, though, in principle, somewhat similar, and, having thus described my present embodiment of the invention what I claim and desire to secure by Letters Patent, is:

1. The combination with an elevator shaft and doors therefor, said elevator having a control lever therein and means operable by the movement of the elevator for locking or unlocking the doors of the shaft, of means carried by the elevator for cooperative engagement with operating means carried by one of the doors. 100

2. The combination with an elevator, shaft, and doors therefor, said elevator having a control lever therein, and means operable by the movement of the elevator for locking or unlocking the doors of the shaft, of horizontally slidable means carried by the elevator and operable by the movement of said door for locking or unlocking the control lever of the elevator. 105

3. The combination with an elevator having a control lever therein, a shaft, and door therefor, and landing, of horizontally movable means carried by the elevator for locking the control lever, normally active door locking means carried on the landing, mechanism operable by the control and carried by the elevator for releasing said door locking means when the elevator is at the landing, and means carried by the door for cooperative engagement with the lever locking means carried by the elevator whereby when the door is open the control lever is locked. 110
